UNITED STATES PATENT OFFICE.

HENRY J. FOSTER, OF CLEVELAND, OHIO, ASSIGNOR TO HYDRAULIC PRESSED STEEL COMPANY, OF CLEVELAND, OHIO, A CORPORATION OF OHIO.

METALLIC REINFORCEMENT FOR CONCRETE.

Application filed April 13, 1920. Serial No. 373,616.

To all whom it may concern:

Be it known that I, HENRY J. FOSTER, a citizen of the United States, residing at Cleveland, in the county of Cuyahoga and State of Ohio, have invented a certain new and useful Improvement in Metallic Reinforcements for Concrete, of which the following is a full, clear, and exact description, reference being had to the accompanying drawings.

This invention relates generally to metallic reinforcements for concrete columns and girders, and more particularly to the novel construction of spacer, intended for use in connection with a helically coiled rod or wire for the purpose of properly positioning said helix and at the same time rendering the reinforcing element stronger. The invention is also in the nature of an improvement upon the spacer disclosed in the application of myself and John Burkhardt, filed April 9, 1920, Serial No. 372,403, the object being to provide for the quicker and easier securing of the coiled rod to the spacer and also to provide a firmer and more binding or locking engagement between the parts.

With these and certain other objects which will become apparent as the description proceeds, the invention consists in the novelties of construction and manipulation hereinafter set forth and pointed out in the appended claims.

In the drawings forming a part of this specification, Fig. 1 is a view of a part of the blank from which the spacer is made; Fig. 2 is a detail perspective view showing a portion of the spacer after the same has been folded; Fig. 3 is a face view of the same after the rod has been connected thereto; and Fig. 4 is a side view of the same.

In carrying out my improvement, I employ a strip of sheet metal A which may be of any desired length and width and any suitable gauge, and the opposite edges of this strip are notched or slotted as shown at B providing oppositely disposed pairs of prongs C. The notches are preferably cut at oblique angles as shown and the inner ends are in transverse alignment, and the ends of the prongs C are also in transverse alignment as most clearly shown in Fig. 1. When the strip is folded longitudinally the

notches will extend in reverse direction but 55 their inner ends will always be in transverse alignment and the ends of the prongs C will also remain in transverse alignment. The shape and relative position of the notches is such that a coil D of the 60 helical rod can be inserted obliquely into a pair of notches and when brought around to a position perpendicular to the axis of the strip said rod will be placed beneath the oppositely projecting prongs C. 65

The helically coiled rod readily permits the individual coils to be separately placed in the series of notches and the inherent resiliency of the coil immediately brings each coil from an oblique (introducing) position to a transverse (seating) position and in order to quickly and easily lock the coil in said seat I bend each pair of prongs toward each other and across and over the rod as most clearly shown in Fig. 3, and this bending of the prongs though easily accomplished serves to bind or lock the rod securely in the seats at the ends of the notches thereby providing a secure connection between the spacer and helically coiled rod. The spacer being made of thin sheet metal materially reduces the cost of production of the reinforcing element as a whole, and by virtue of the fold or longitudinal bend therein great rigidity and strength is imparted to said spacer which perceptibly increases the facility with which the unit can be handled in setting up.

It will be understood that any desired 90 number of spacers can be used in connection with a single helical coil.

Having thus described my invention, what I claim is:—

1. A spacer for spiral reinforcements comprising a folded strip of metal the edges of said strip having pairs of oppositely projecting prongs beneath which a rod can be inserted, said prongs being bendable towards each other to lock said rod in engagement with said edges. 95

2. A spacer for spiral reinforcements comprising a longitudinally folded strip of sheet metal the edges thereof being notched and having opposed pairs of oppositely projecting prongs beneath which a rod can be inserted, said prongs being bendable towards each other to lock said rod in engagement with said folded strip. 100 105

3. A spacer for spiral reenforcements comprising a folded strip of metal, the edges of said strip having reversely inclined notches, the inner ends of said notches being in transverse alignment, and providing oppositely disposed prongs also in transverse alignment, the ends of said prongs being bendable toward the longitudinal center of said bar.
4. A spacer for spiral reenforcements comprising a folded strip of metal, the edges of said strip having oppositely projecting prongs adapted to engage opposite sides of a rod inserted beneath said prongs, said prongs being bendable towards each other across said rod, to lock the same in engagement with said spacer.
5. A metallic reenforcement comprising a helically coiled rod, and a spacer strip having spaced wings, said wings being notched to provide seats for the coils of said rod, the projecting edge portions of said wings being bent toward the longitudinal center of said bar and across said rod.
6. A metallic reenforcement comprising a helically coiled rod, and a longitudinally folded sheet metal strip, the edges thereof being oppositely slotted, providing opposed pairs of prongs, beneath which the coils of the rod are seated, said prongs being bent inwardly toward each other to lock said coil in its seat.

In testimony whereof, I hereunto affix my signature.

HENRY J. FOSTER.
